(57) **CLAIM**

The ornamental design for a display screen with animated graphical user interface, as shown and described.

DESCRIPTION

FIG. 1 is a front view of the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is the tenth image thereof;

FIG. 11 is the eleventh image thereof;

FIG. 12 is the twelfth image thereof; and,

FIG. 13 is the thirteenth image thereof.

The broken line showing of certain icons and of the remainder of the display screen is for environmental purposes only and forms no part of the claimed design.

The appearance of the transitional image sequentially transitions between the images shown in FIGS. 1-13. The process or period in which one image transitions to another image forms no part of the claimed design.
